UNITED STATES PATENT OFFICE.

IRVING M. SYLVESTER, OF PROVIDENCE, RHODE ISLAND, ASSIGNOR TO
PARKS BROS. & ROGERS, OF PROVIDENCE, RHODE ISLAND, A FIRM.

STUD OR BUTTON.

No. 820,683.

Specification of Letters Patent.

Patented May 15, 1906.

Application filed June 12, 1905. Serial No. 264,844.

To all whom it may concern:

Be it known that I, IRVING M. SYLVESTER, a citizen of the United States, residing at Providence, in the county of Providence and State of Rhode Island, have invented a new and useful Improvement in Studs or Buttons, of which the following is a specification.

This invention has reference to an improvement in studs or buttons, and more particularly to an improvement in pipe-stem studs used generally in shirt-bosoms.

The object of my invention is to improve the construction of a pipe-stem stud, thereby simplifying and strengthening the construction and reducing the cost of manufacturing the stud.

My invention consists in the peculiar and novel construction of a pipe-stem stud having a head, a hollow L-shaped shank forming integral the tubular stem and shoe of the stud, a sliding locking-bar having annular grooves in the shoe, and means formed integral with the shoe adapted to engage with the grooves in the locking-bar to hold the locking-bar in either the closed or extended position, with details of construction, as will be more fully set forth hereinafter.

Figure 1 is a face view of my improved stud, showing the locking-bar in the extended position. Fig. 2 is a view looking at the side of the stud with the locking-bar in the extended position. Fig. 3 is an enlarged sectional view taken on line X-X of Fig. 2, showing the spring-snap formed integral with the shoe of the stud. Fig. 4 is an enlarged sectional view taken lengthwise through the stud, showing the spring-snap engaging with a groove in the locking-bar to hold the same in the extended position; and Fig. 5 is an enlarged cross-sectional view taken on line Y-Y of Fig. 3 through the shoe, spring-snap, and locking-bar of the stud.

In the drawings, *a* indicates the head, *b* the L-shaped shank forming integral the tubular stem *c*, the tubular shoe *d*, and the spring-snap *e*, and *f* the sliding locking-bar, of my improved stud.

The head *a* may be of any material or configuration and secured to the stem *c* in any well-known way. In the drawings the head *a* is shown as a semispherical shell *a'*, secured to the disk *a''* by spinning the edge of the

shell over the edge of the disk, which in turn is secured to the open end of the stem *c* by solder.

55

The shank *b* is constructed of hollow spring-wire bent L shape to form a tubular stem *c* and tubular shoe *d*, as shown in Fig. 4. A hole *b'* is formed in the bend of the shank *b* for the locking-bar *f*, which is held in the tubular shoe *d* and extends through the hole *b'* when the bar is in the extended position. The snap *e* has the inwardly-extending transverse rib *e'*, adapted to enter a groove in the locking-bar and hold the same in either the closed or extended position. The snap *e* is formed integral with the tubular shoe *d* by cutting the two longitudinal parallel closely-associated slits *b'' b''* through the shoe, as shown in Fig. 3, and then stamping in the central transverse rib *e'* on the spring-strip formed by the slits *b'' b''*, as shown in Figs. 4 and 5.

60

The sliding locking-bar *f* is constructed from a round bar to have the annular grooves *f'* and *f''*, the slightly-enlarged end *f''*, and the usual pointed end *f''* to facilitate the entering of the shoe *d* and stem *c* of the stud in the stud or button hole of a shirt-bosom.

65

In the use of my improved stud the locking-bar *f* is pushed through the shoe *d* into the closed position by pushing on the end *f''* of the bar. This brings the rib *e'* on the spring-snap *e* into the groove *f'* in the locking-bar, firmly holding the same in the closed position under spring tension. The pointed end *f''*, the shoe *d*, and the stem *c* are now pushed through the stud-hole in the shirt-bosom. The locking-bar *f* is then pushed into its extended or locked position on the back of the shirt-bosom by pushing on the end *f''* and held in this position by the rib *e'* on the spring-snap *e* entering the groove *f''* in the locking-bar, as shown in Fig. 4, thus securely locking the stud to the shirt-bosom.

70

80

Having thus described my invention, I claim as new and desire to secure by Letters Patent—

85

In a pipe-stem stud, a head, a hollow L-shaped shank forming a tubular stem and shoe, a locking-bar formed with annular grooves extending in said shoe, said shoe being formed with a pair of longitudinal parallel closely-associated slits intermediate its

90

95

length, which slits extend to points adjacent the ends of said shoe, the material between said slits forming a snap supported by each of its ends from said shoe, said snap having
5 an inwardly-transverse rib formed central of its length to engage in said grooves of the locking-bar.

In testimony whereof I have signed my name to this specification in the presence of two subscribing witnesses.

IRVING M. SYLVESTER.
